UNITED STATES PATENT OFFICE.

HUGO HEINRICH, OF ZWICKAU, GERMANY.

ENGINE, PUMP, COMPRESSOR, AND THE LIKE.

Application filed December 24, 1926, Serial No. 156,777, and in Germany November 27, 1925.

My invention relates to improvements in engines, pumps, compressors, and the like, and more particularly in engines, pumps or compressors of the type comprising a fixed cylinder and a movable cylindrical piston disposed eccentrically in the said cylinder and including a crescent-shaped working chamber divided by a transverse partition into two sections adapted alternately to receive and deliver the fluid, the said cylinder and piston being movable relatively to each other so as to cause the said crescent-shaped working chamber to be shifted around the cylinder and to increase and decrease the capacity of the sectional chambers.

One of the objects of the present improvements is to provide an engine, pump or compressor of this type, in which rotary movement of the cylindrical piston is prevented, and in which the cylindrical piston encloses the said stationary cylinder, and in which the alternate increase and decrease of the capacity of the said sectional chambers is brought about by imparting circular oscillating movement to the piston.

For the purpose of explaining the invention several examples embodying the same are shown in the accompanying drawings, in which the same letters of reference have been used in all the views to indicate corresponding parts, and in which,

Fig. 1, is a sectional elevation showing the improved apparatus in the form in which it acts as a compressor or pump, the section being taken on the line 1—1 of Fig. 2,

Fig. 2, is a sectional elevation taken on the line 2—2 of Fig. 1,

Figs. 3 and 4 are similar views as Fig. 1 showing modifications,

Fig. 5, is a section taken on the line 5—5 of Fig. 4,

Fig. 6, is a partial sectional elevation showing the stationary cylinder of another modification, and

Fig. 7, is a sectional elevation taken on the line 7—7 of Fig. 6.

According to Fig. 1, 1 is a substantially cylindrical casing supported by feet 61 on a suitable foundation. 2 are heads fixed to the two ends of the casing 1 and provided with inwardly directed concentric cylindrical projections 4. A shaft 43 is rotatably mounted in the heads 2 in anti-friction bearings 3. A guide member is fixed to the shaft 43 comprising a hub 9, a central web 62 and cylind-

rical flanges 10 projecting from the web 62 on opposite sides, and being disposed eccentrically of the shaft 43. Two cylindrical pistons 5 are guided on the inner faces of the flanges 10 through the intermediary of anti-friction rollers 11 and are formed with outwardly projecting flanges 63 bearing on the inner walls of the heads 2 and inwardly directed flanges 64 guided on the web 62 by means of anti-friction rollers 12 and engaging the inner faces of the projections 4. By disposing the flanges 10 eccentrically of the shaft 43 the pistons 5 and the cylindrical projections 4 are eccentric relatively to each other enclosing crescent-shaped chambers divided by radial partitions 7 into two sectional chambers 6 and 6', the pistons 5 and the cylindrical projections 4 making contact with each other at one side, as is shown in Fig. 1. The partitions 7 are made integral with cylindrical hubs 7' rotatably mounted on the hub 9, anti-friction rollers 65 being interposed between the hubs 9 and 7'.

The heads 2 and the projections 4 are made hollow, and the chambers thus provided are divided by radial partitions 66 and 67 into two chambers 68 and 69, adapted to alternately communicate with the sectional chambers 6 and 6'. In the position of the pistons 5 shown in Fig. 1 the chamber 69 communicates with the sectional chamber 6 through a port 15, and the chamber 68 communicates with the chamber 6' through a port adapted to be closed by a spring pressed valve 16. The heads 2 are provided with tubular extensions 70 and 71 by means of which the chambers 68 and 69 are connected to intake and delivery pipes.

The partitions 7 extend between the partitions 67, 67, and in order to insure air or liquid tight engagement between the parts, they are guided between a pair of cylindrical boxes 8 rockingly mounted between cylindrical bearing faces formed on the partitions 67, 67.

In the preferred construction shown in the figures the hub 9 is not directly keyed to the shaft 43 but is mounted on eccentric disks 19 fixed to the said shaft and engaging eccentric bores 72 of the hub 9, the object of the said eccentric disks being to permit readjustment of the member 9, 10 and the pistons 5 in case of wear. It will be understood that the outer circumferences of the cylindrical projections 4 must always be in tight

engagement with the inner cylindrical circumferences of the pistons 5, because otherwise the fluid would be able to flow from the sectional chamber 6' into the sectional chamber 6. If the said cylindrical faces are worn, the eccentric disks 19 are readjusted on the shaft 43 and within the hub 9, so that the pistons and cylinders are again in close engagement.

10 In my improved apparatus, rotary movement of the pistons 5 is made impossible. To show what may be done, the said pistons are connected by links 13 to relatively fixed points 74, the said links permitting 15 merely an oscillating movement of the pistons 5.

As to the operation of the apparatus it will be assumed that the apparatus acts as a pump. When the shaft 43 is rotated by 20 means of a belt passing over a belt pulley 14 in the direction of the arrow α shown in Fig. 1, the member 9, 10 is rotated in the same direction, and acts through the intermediary of the anti-friction rollers 11 on 25 the pistons 5. Therefore the said pistons are pressed upwardly at their bottom sides and towards the axis of the shaft 43, the partition 7 being simultaneously retracted inwardly by being mounted on the hub 9. 30 Thus, the points of contact between the pistons 5 and the cylinders 4 gradually move from the position shown in Fig. 1 in the direction of the arrow α , thus reducing the volume of the chambers 6' and propelling the 35 fluid confined therein through the valves 16, the chambers 68, and the tubular members 70. Simultaneously, the volume confined within the chambers 6 is increased, so that the fluid is taken into the same through the 40 ports 15, the chambers 69 and the tubular intake passages 71. After the said point of contact has passed beyond the delivery valves 16 and the ports 15, conditions are reversed, the valves 16 being now connected with the 45 sectional chambers 6, and the ports 15 with the sectional chambers 6'. The capacity of the chambers 6' is gradually increased, and that of the chambers 6 decreased, so that fluid is now taken into the sectional chambers 6' and through the ports 15, while the fluid within the chambers 6 is first compressed and thereafter delivered through the 50 valves 16.

It will be understood that the said operation of alternately increasing and decreasing the capacity of the sectional chambers 6 and 6' is performed without rotary movement being imparted to the pistons 5, such rotary movement being prevented by the links 13 55 permitting only oscillating movement of the pistons. Therefore, the sliding surfaces 17 and 18 which in connection with the partitions 7 and the point of contact of the two circular peripheries enclose the working 60 chambers, have, even when the engine is 65

running at a high number of revolutions, a comparatively low speed, and will therefore bear a packing pressure which renders the packing effective.

The drawing shows the machine or engine 70 as a twin arrangement so as to mutually oppose the axial pressures, but it is obvious that the machine or engine may also be built as a single cylinder machine or engine in which the axial pressures are taken up by 75 ball bearings or the like, which are then supported against the casing or the covers.

In the construction so far described, rotary movement of the piston 5 is prevented by means of the link 13 which is pivotally 80 mounted on the fixed point 74. Now, when the movement of the piston is followed it will be understood that the bottom part thereof is moved substantially along a circle, the center of which coincides with 85 the fixed point 74, while all the other points, and more particularly the top part of the piston have, in addition, a horizontal movement. The horizontal movement of the top part of the piston is comparatively large, 90 and it is double that of the portions of the piston intersected by a horizontal plane passing through the axis of the pump. Therefore the resistance by inertia of the 95 piston is comparatively large.

In Fig. 3, I have shown a modification in which the said resistance by inertia is reduced, so that the pump or engine can be operated at higher velocity. As shown in the said figure, the means for preventing 100 rotary movement of the pistons are constructed so that all the points have the same oscillatory paths. As shown in the said figure, the pistons 5 carry at diametrically opposite parts, trunnions 20 which are longitudinally slidable in sleeves 22 fixed to or made integral with a member 23 carrying further sleeves 22' guided on trunnions 21 fixed to the wall of the casing 1. Therefore, when the pistons 5 are operated in the 105 manner described with reference to Figs. 1 and 2 by means of the eccentric flanges 10, rotary movement of the pistons is prevented by the trunnions 20, while oscillatory movement is permitted by the said trunnions being axially shiftable in the sleeves 22, and the sleeves 22' being axially shiftable on the trunnions 21. Thus all the points of the pistons perform circular oscillatory 110 movements which are equal to the circular path of the eccentric axis of the pistons 5 around the axis of the shaft 43. The member 23 provides a link having the same function as the link 13 shown in Fig. 1, in which however, the length of the link in a geometrical sense is infinite.

Otherwise, the construction of the machine is the same as has been described with reference to Figs. 1 and 2.

In Figs. 4 and 5, I have shown a modifi- 130

cation in which additional working chambers are provided internally of the stationary cylinder, the sleeve carrying the transverse partition 7 providing the piston of the said cylinder.

As shown in the said figures, the apparatus comprises a cylindrical casing 80 provided at one end with a hollow head 82 and at its opposite end with a head 83. In anti-friction bearings 84 a rotary shaft 85 is mounted, which carries a pulley 86. The hollow head 82 is made integral with a hollow cylinder 87 which extends inwardly from the said head to a plane spaced from the head 83, and which is disposed concentrically of the shaft 85. To the shaft 85 an eccentric cylindrical member 88 is keyed, which provides a bearing for a sleeve 89 made integral with a radial partition 90 extending through a pair of segmental cylindrical blocks 91 rockingly mounted in cylindrical bearing faces 92 provided in the cylinder 87, anti-friction bearings 93 being preferably interposed between the sleeve 89 and member 88. The cylinder 87 is surrounded by a cylindrical piston 94 bearing with a flange 95 on the inner face 97 of the head 82, and formed with an inwardly projecting flange 98, by means of which it is rigidly connected with the sleeve 89.

The outer surface of the cylinder 87 and the inner surface of the piston 94 are in contact with each other along a line travelling in the operation of the apparatus circumferentially around the cylinder. Thus, a crescent-shaped chamber is provided between the said cylinder and piston, which is divided by the partition 90 and the said line of contact into two sectional chambers 100 and 101. In a similar way, the outer circumference of the sleeve 89 makes contact with one line with the inner circumference of the cylinder 87, and the crescent-shaped chamber thus produced between the outer circumference of the sleeve 89 and the inner circumference of the cylinder 87 is divided by the inner portion of the partition 90 and the said line of contact into two chambers 102 and 103. Within the hollow cylinder 87 four longitudinal segmental passages 104, 105, 106 and 107 are formed, and the passages 104 and 105 may communicate through valves 108 and 109 each with one of the sectional chambers 100, 101 and 102, 103, while the passages 106 and 107 may communicate with the same chambers through ports 110 and 111. The said passages 104, 105, 106 and 107 are in communication with the interior of the head 82, and they are separated from each other by suitable partition walls. The chambers thus produced within the head 82 may be connected with pipes (not shown) for supplying and delivering the fluid thereto. Thus, when the apparatus is operated as a pump or compressor, the passage 107 com-

municates with the supply of the liquid or gas, which upon operation of the piston 94 in the direction of the arrow y is taken into the chamber 100. After the line of contact between the piston 94 and the outer circumference of the cylinder 87 has passed beyond the valves 108, the liquid or gas confined within the chamber 100 is delivered into the passage 104.

Rotary movement of the piston 94 is prevented by suitable means, Fig. 4 showing a link 112. But I wish it to be understood that other means may be provided in lieu of the said link, and that in the preferred construction the mechanism shown in Fig. 3 is provided in the apparatus illustrated in Figs. 4 and 5.

In workshop constructions it is always difficult to work the machine in such a way that the circumferences of the inner piston 89 and of the outer piston 94 are simultaneously and permanently in contact with the corresponding surfaces of the stationary hollow cylinder 87. Play will ensue particularly when after considerable use the individual surfaces become worn. But even the assembly of a new machine or engine causes difficulties, as it is of course desirable that the contact surfaces referred to should run together under a certain tension. Figs. 6 and 7 show an arrangement which overcomes the difficulties indicated. The general construction of the machine or engine is the same as that above described. The difference is to be found in the fact that the sleeve 115, which forms the inner piston, and the outer piston 116 are constructed apart each being controlled by special eccentric cams. On the shaft 117 is the eccentric cam 118 which in its rotation causes the sleeve 115 to oscillate and so sets up the working effect of the inner chamber. The outer piston 116 receives its movement from a driving ring or cylinder 120 which radially supports the piston 116 through ball bearings 121 and axially through ball bearings 122. The driving ring or cylinder 120 can thereby have the same eccentricity as the eccentric cam 118 or any other eccentricity.

Both eccentricities are adjustable in themselves in order to ensure a proper fitting together of the circumferences encircling the working chamber. For this purpose eccentric bushings 123 are arranged on the shaft 117, the eccentric cam 118 being adjustably fixed to said bushings. The driving ring, or cylinder, 120 also lies on two eccentric bushings 125 and 126, of which 126 is keyed to the shaft and 125 is adjustably mounted on 126. Fig. 6 shows a cross section through the inner chamber of the machine, or engine, on an enlarged scale, in order to show clearly the mode of varying the eccentricity. The eccentric bushings 123 having an eccentricity 127 is firmly keyed to the shaft 117,

and on 123 is the adjustable eccentric cam 118 having an eccentricity 128. In the position shown on the drawing, the machine, or engine, thus has the relative eccentricity 129. If the eccentric cam 118 is rotated, the eccentricity 128 also moves in a circle around the centre of the eccentric cam 123 and increases or diminishes the relative eccentricity 129, so that the circumference of the sleeve 115 can be brought towards the inner circumference of the hollow cylinder 130. The same method can be applied absolutely independently with respect to the outer piston, as the driving ring or cylinder 15 likewise may be mounted on two different eccentrics 125 and 126 one within the other, so that the eccentricity of the driving ring or cylinder can also be altered as desired.

The working chambers 131 and 132 have different dimensions, the proportions of which are determined by the selected internal and external diameter of the stationary cylinder 130. Thus, the greatest economy possible in working the machine, or engine, is also attained with a two-stage expansion of the power medium or compression of the working medium. It is also possible to arrange the working chambers in such a way that they act in parallel, by which means the efficiency of the machine or engine is increased.

So far it has been assumed that the apparatus is used as a pump or compressor. If it is used as an engine, the driving fluid is of course supplied in the reverse direction. For example, in Fig. 1, the driving fluid is supplied through the valve 16, suitable mechanism being provided for opening and closing the said valve at the proper time. The pressure fluid admitted to the sectional chamber 6' tends to enlarge the said chamber, thus rotating the piston 5 in a direction opposite to the arrow α . Thus the line of contact between the piston 5 and the cylinder 4 travels around the cylinder until it passes the port 15, whereupon the fluid escapes through the port 15.

In a similar way the pressure fluid is supplied to the apparatus shown in Figs. 3 to 7. While in the above description of the invention reference has been made to particular embodiments thereof I wish it to be understood that my invention is of course not limited to these constructions as obviously various changes may be made in the general arrangement of the apparatus and the construction of its parts without departing from the invention.

I claim:

1. In an apparatus of the class described, the combination with a casing, of a fixed cylinder and a movable cylindrical piston eccentrically mounted one within the other and in contact with each other along a line parallel to their axes so as to pro-

vide a crescent-shaped working chamber, a cylindrical guide member rotatably mounted in said casing, a partition wall extending transversely through said working chamber and yieldable in radial direction, means to impart oscillating movement to said piston for causing the said line of contact to travel around said cylinder, means preventing rotary movement of said piston while permitting the said oscillating movement thereof, and a fluid supply and discharge to and from the sections of the crescent-shaped working chamber separated from each other by said partition.

2. In an apparatus of the class described, the combination with a casing, of a fixed cylinder, a movable cylindrical piston eccentrically mounted around said cylinder and in contact therewith along a line parallel to its axis so as to provide a crescent-shaped working chamber, a cylindrical guide member rotatably mounted in said casing, a partition wall extending transversely through said working chamber and yieldable in radial direction, means to impart oscillating movement to said piston for causing the said line of contact to travel around said cylinder, a link connected to said piston preventing its rotary movement while permitting oscillating movement thereof, and a fluid supply and discharge to and from the sections of the crescent-shaped working chamber separated from each other by said partition.

3. In an apparatus of the class described, the combination with a casing, of a fixed cylinder, a movable cylindrical piston eccentrically mounted around said cylinder and in contact therewith along a line parallel to its axis so as to provide a crescent-shaped working chamber, a cylindrical guide member rotatably mounted in said cylinder, a partition wall extending transversely through said working chamber and yieldable in radial direction, means to impart oscillating movement to said piston for causing the said line of contact to travel around said cylinder, mechanism connected with said piston for guiding the same so that each point thereof moves through a circle having a radius equal to the eccentricity of the piston relatively to the cylinder, and a fluid supply and discharge to and from the sections of the crescent-shaped working chamber separated from each other by said partition.

4. In an apparatus of the class described, the combination with a casing, of a fixed cylinder, a movable cylindrical piston eccentrically mounted around said cylinder and in contact therewith along a line parallel to its axis so as to provide a crescent-shaped working chamber, a cylindrical guide member rotatably mounted in said cylinder, a partition wall extending transversely through said working chamber and yieldable in radial direction, means to impart oscillating move-

ment to said piston for causing the said line of the link, and a fluid supply and discharge of contact to travel around said cylinder, a link mounted on a relatively fixed part for moving transversely of the axis of said piston and connected with said piston for permitting movement thereof in a direction transverse of the said direction of movement to and from the sections of the crescent-shaped working chamber separated from each other by said partition. In testimony whereof I have affixed my signature.

HUGO HEINRICH.
